UNITED STATES PATENT OFFICE.

ORVILLE M. MORSE, OF JACKSON, MICHIGAN.

PALLET FOR MOLDS.

No. 815,109.

Specification of Letters Patent.

Patented March 13, 1906.

Application filed August 24, 1904. Serial No. 221,918.

To all whom it may concern:

Be it known that I, ORVILLE M. MORSE, of Jackson, in the county of Jackson and State of Michigan, have invented certain new and 5 useful Improvements in Pallets for Molds; and I hereby declare that the following is a full, clear, and exact description thereof, reference being had to the accompanying drawings, which form part of this specification.

10 In molds for forming cement building-blocks and the like effort has been made to employ pallets of wood on account of their lightness and cheapness; but such pallets have heretofore usually been found unsatisfactory. In use a pallet is placed in the bottom of the mold in which the cement block is to be formed and after the cement has been poured in and is sufficiently set the block is removed from the mold and allowed to dry 15 out without being removed from the pallet. In consequence the pallet is subjected first to the action of moisture, which permeates it to a greater or less degree, and later to a slow drying process, which is retarded on one face 20 by its contact with the slowly-setting block. Under these conditions the pallet quickly warps out of shape to such an extent as to be useless and has to be discarded.

The object of my invention is to provide a 25 pallet the body whereof is of wood which is so reinforced with metal as to be prevented from warping and generally strengthened.

In the drawings I have shown, in Figure 1, a section of a pallet embodying my invention, showing in dotted lines a mold where-with it may be used. Fig. 2 is an isometric perspective of the pallet shown in Fig. 1.

In the drawings like numerals of reference in both figures refer to like parts.

30 Referring now to the drawings, 5 indicates the wood pallet-body, which is usually a flat plate of wood having its grain extending lengthwise therethrough and cut to suit the internal configuration of the mold. Some 35 molds are provided with central cores, in which case the pallet-body, as indicated in the drawings, is cut away, as at 6, to receive the core; but usually the pallet-body is solid throughout. In combination with the wood 40 body of the pallet I employ reinforcing metal pieces arranged to resist the warping tendency of the wood. To this end I arrange metal reinforcing-pieces preferably at or near the ends of the pallet-body to extend trans- 45 versely of the grain of the wood, so as to prevent the pallet from warping or curling. 50 Furthermore, I prefer to embed the metal pieces wholly or partially in the wood body and so arrange them that they permit the normal expansion and contraction of the 55 wood, while preventing the warping thereof. In the specific construction 7 indicates a metal reinforcing-piece, preferably a piece of sheet metal folded upon itself to afford a double thickness and embedded wholly in the 60 wood, preferably midway between the top and bottom surfaces thereof and preferably extending transversely of the body from side to side and longitudinally to any suitable depth. A single sheet of metal might be employed with some advantage; but I prefer the doubled construction shown, for the reason that the spring tendency of the two leaves of the piece 7 tends to maintain the strip in position. 75

8 indicates in general a reinforcing-piece comprising a central portion 9, preferably of greater length than the width of the pallet-body, and edge portions 10 10 of length substantially equal to the width of the pallet-body, the edges 10 10 being bent inward and preferably then doubled back upon themselves in such a way that said edge portions converge somewhat from a maximum distance of separation at their juncture with the 85 body 9 toward their free doubled ends, the area inclosed thereby being of dovetailed shape.

A portion 12 of the end of the pallet extending across the same from side to side is similarly shaped, being preferably formed by sawing converging grooves in the end of the pallet parallel in the direction of their length and converging in the direction of their depth and of a depth and thickness corresponding 90 with the depth and thickness of the bent edge portion 10 of a metallic piece. The metallic reinforcing-piece is usually inserted in these grooves endwise, and when in place the portions 9' of the central body 9, projecting beyond the edge portion 10, are bent down over the side of the wood body, as shown in Fig. 2. Preferably the bent end portions or ears 9' do not closely fit against the sides of the wood body when the latter is in dry condition, so that 95 certain amount of swelling of the wood may be accommodated without pressure against the ears 9'. It will be apparent that the method of inserting the reinforcing-piece 8 permits of expansion and contraction of the 100 wood laterally practically without resistance; but the wood body is greatly strengthened 105 110

and rigidly held against warping. At the right end of Fig. 1 I have shown the pieces 7 and 8 as separate; but they might be formed of a single piece, as shown at the left end of said figure, the ears 9' being in such cases bifurcated, as at 9".

When the pallet is provided with an opening 6, as heretofore described, I prefer also that the portions of the wood body at the end of the opening 6 be reinforced by strips 13, preferably of a single thickness, inserted therein preferably in substantially the same plane as the reinforcing-pieces 7 heretofore adverted to.

15 It will be apparent that in practice the ears 9' might be omitted and the piece 8 left without other securing means than its engagement with the wood body, or that other suitable holding means might be employed, such 20 as will permit the swelling and contraction of the wood without material hindrance. It will also be apparent that either the piece 7 or the piece 8 might be separately used with some advantage.

25 While I have described in some detail a specific embodiment of my invention, the details of which I believe to be new and advantageous, it will be apparent that its broad features are capable of embodiment in many 30 forms, and I do not desire to be understood as limiting myself to the specific construction shown and described further than set forth in the claims.

Having thus described my invention, what 35 I claim, and desire to secure by Letters Patent of the United States, is—

1. A pallet for molds comprising a wood body and a metal reinforcing-piece, having a central portion overlying an end portion of 40 the wood body and having on each side of its median line a single bend, the bent edge portions projecting beyond the central portion and being embedded in the wood.

2. A pallet for molds comprising a wood 45 body and a metal reinforcing-piece having a central portion overlying and substantially

completely covering an end of the wood body, and inturned edge portions, the free edges whereof are separated a distance less than the width of the central portion, said edge 50 portions embracing therebetween a body of the wood.

3. A pallet for molds comprising a wood body having at its end a portion of dovetailed shape narrower toward the middle of the 55 body than at its free extremity and a metal reinforcing member of similar configuration having its edges embracing the dovetailed portion of the wood.

4. A pallet for molds comprising a wood 60 body and a metal reinforcing-piece substantially covering an end of said body, having inturned portions embedded in the wood body to retain said piece upon the body.

5. A pallet for molds comprising a wood 65 body, and a metal reinforcing-piece having a part extending along the end of the wood from side to side thereof, a portion embedded in the body of the wood, and ears projecting from the first said portion bent down over the 70 sides of the wood body.

6. A pallet for molds comprising a flat wood body having formed in the ends thereof grooves parallel in the direction of their length, and converging in the direction of 75 their depth to include between them a wood portion of dovetailed shape, and a metal reinforcing-piece having a central portion overlying the end of the wood body, and inturned edges interfitting in said grooves.

80 7. An article of manufacture consisting of a pallet for molds comprising a wood body having an aperture therein, reinforcing-pieces secured to its ends, and metal pieces embedded in the wood adjacent the aperture.

85 In testimony that I claim the foregoing as my own I affix my signature in presence of two witnesses.

ORVILLE M. MORSE.
